FIG. 7.

William W. Bateman,
INVENTOR

BY *Victor J. Evans*

ATTORNEY

WITNESS:

UNITED STATES PATENT OFFICE.

WILLIAM WILSON BATEMAN, OF SUNBURY, PENNSYLVANIA, ASSIGNOR OF TWENTY-FIVE AND ONE-HALF PER CENT TO JOHN A. BATEMAN, OF SUNBURY, PENNSYLVANIA, AND TWENTY-FIVE AND ONE-HALF PER CENT TO HUGH C. CURRY, OF DANVILLE, PENNSYLVANIA.

RAIL CHAIR AND SPLICE PLATE.

Application filed September 3, 1927. Serial No. 217,378.

This invention relates to improvements in rail chairs and splice plates, the general object of the invention being to provide means for firmly holding the rails to the ties and 5 for fastening the ends of the rails together, the parts being so arranged that rails can be quickly and easily put in place.

Another object of the invention is to so form the fish plates that they will clamp the 10 ends of the rails together without the use of bolts and to provide means whereby the spikes for the chairs and fish plates are driven through depending portions into the sides of the ties.

15 Another object of the invention is to make the fish plates and the chairs of sections which are so formed that a wedging action is set up when the sections are placed together which acts to clamp the rail or rails in place, while 20 permitting expansion and contraction of the rails.

This invention also consists in certain other features of construction and in the combination and arrangement of the several parts, to 25 be hereinafter fully described, illustrated in the accompanying drawings and specifically pointed out in the appended claims.

In describing my invention in detail, reference will be had to the accompanying drawings 30 wherein like characters denote like or corresponding parts throughout the several views, and in which:—

Figure 1 is a longitudinal sectional view through a portion of a track showing my invention in use.

Figure 2 is a plan view of Figure 1.

Figure 3 is a section on line 3—3 of Figure 4.

Figure 4 is a section on line 4—4 of Figure 2.

Figure 5 is a section on line 5—5 of Figure 2.

Figure 6 is a top plan view of a chair showing the sections thereof partly separated.

45 Figure 7 is a horizontal sectional view through a pair of fish plates, showing the same partly separated.

In these drawings, A indicates a chair for fastening a rail B to a tie C, this chair comprising 50 a pair of sections 1 and 2, each section being formed with an overhanging flange 3 for engaging the top side of one por-

tion of the base of a rail when the rail is seated upon the chair, as clearly shown in Figure 4. The inner edge of each section is 55 inclined, as shown at 4, and adjacent the inclined edge, each section is formed with a dovetail groove 5 which forms a dovetail tongue 6 which engages the groove in the other section. The grooves open out at the 60 inner end of each section, the outer end of each section being formed with a depending flange 7 which closes the groove. Thus when the two sections are pushed together with their tongues engaging the grooves, one section moves toward the other section so that the flanges 3 will set up a clamping action on the base of the rail and thus clamp the rail in the chair. The flanges 7 engage the sides 65 of the tie and spurs 8 are formed on the flanges which penetrate the tie, as shown in Figure 3. Spikes 9 are driven through holes in the flanges into the tie, as also shown in Figure 3, to hold the chair to the tie. At the top of the inner wall of each flange 7 is an 70 overhanging part 10 which fits in a recess 11 in the inner end of the other section, when the two sections are brought together.

The fish plates 12 and 13, used for connecting the abutting ends of two rails together, 75 are made similar to the sections of the chair, but the inner edges of the flanges 3' of the fish plates are extended upwardly, as shown at 14, with their upper ends enlarged and shaped to fit the under side of the head of the rail, as 80 shown in Figure 5. These extensions 12 are reinforced by the webs 15. These plates 12 and 13 are also formed with depending flanges 7' for engaging the sides of the ties and these flanges are provided with holes so that spikes 90 can be driven into the sides of the ties. These flanges are also provided with the spurs 8'. The fish plates are also formed with the outwardly extending ears 16 having spike receiving holes therein so that spikes can be 95 driven into these ears into the tops of the ties, as shown at 17.

When putting a track in position, one-half of a chair is slipped between the rail and tie and spiked and then the other half is 100 slipped on from the wider end on the other side of the rail and spiked. As before stated, the pushing together of the two halves or sections of the chair sets up a clamping ac-

tion on the base of the rail so that after the chairs are spiked to the tie, the rail is firmly held in place. The fish plates are assembled in the same manner and these plates are held 5 in position not only by the spikes in the sides of the ties, but also by the spikes passing through the ears 16 into the tops of the ties, these latter spikes acting to keep the ties from spreading. As will be seen, this form of fish 10 plate assembly will firmly hold the rail ends together without the use of bolts so that it is not necessary to drill holes in the rails. By driving spikes into the sides of the ties, there is less danger of them working loose and the 15 ties will last longer, due to the fact that there are but few holes in the upper surfaces of the ties. When the weight of a train comes on the rails, the fish plates will clamp the rails under their heads so that the rails are firmly 20 held together without the use of bolts and thus the rails are not weakened by having holes bored therein.

A wear plate 18 is placed under each chair and pair of splice plates and each structure is 25 also provided with a pair of depending parts 19 which rest upon the wear plate and a central projection 20 which forms a fulcrum for a rail, as clearly shown in Figures 4 and 5.

It is thought from the foregoing description 30 that the advantages and novel features of my invention will be readily apparent.

I desire it to be understood that I may make changes in the construction and in the combination and arrangement of the several

parts, provided that such changes fall within 35 the scope of the appended claims.

What I claim is:—

1. Means for fastening a rail to a tie of a track comprising a chair formed in sections, each section comprising a base and an over- 40 hanging flange, the inner edge of the base of each section being tapered, a dovetail groove and a dovetail tongue formed at the inner edge of each section, the tongue on one section engaging the groove on the other, a depending part at the outer end of each section covering the end of the groove in said section, and means for fastening the chair to the tie. 45

2. Means for fastening a rail to a tie of a track comprising a chair formed in sections, each section comprising a base and an over- 50 hanging flange, the inner edge of the base of each section being tapered, a dovetail groove and a dovetail tongue formed at the inner edge of each section, the tongue on one section engaging the groove on the other, a depending flanges at the outer ends of the sections for engaging the sides of the tie and spikes driven through the holes in the flanges 60 and entering the sides of the tie each of said flanges covering the end of the groove in the section and each section having an overhanging part at one end and a recess at its other end, the recess of one section receiving the overhanging part of the other section. 65

In testimony whereof I affix my signature.

WILLIAM WILSON BATEMAN.
